UNITED STATES PATENT OFFICE.

JOHN JAY LESCHER, OF MOUNT CARMEL, ILLINOIS, ASSIGNEE OF ONE-HALF TO
CLARENCE HURD, OF MOUNT CARMEL, ILLINOIS.

GRINDING-MACHINE.

1,219,827.

Specification of Letters Patent. Patented Mar. 20, 1917.

Application filed April 29, 1916. Serial No. 94,312.

To all whom it may concern:

Be it known that I, JOHN JAY LESCHER, a citizen of the United States, residing at Mount Carmel, in the county of Wabash and State of Illinois, have invented certain new and useful Improvements in Grinding-Machines, of which the following is a specification.

My invention relates to improvements in grinding machines, the present embodiment of the invention being particularly designed and adapted for use in grinding engine cylinders and in which a grinding member or abrading tool is simultaneously rotated and revolved around the axis of the cylinder in contact with the wall and fed longitudinally thereof so that the entire surface will be ground and any imperfections therein removed in the grinding operation.

The primary object of my invention is to provide a generally improved grinding machine of this class or type which will be exceedingly simple in construction, cheap of manufacture, and efficient in use.

A further object of the invention is the provision of improved bearings of great strength and rigidity adapted to carry and maintain the parts in proper relative positions in the various movements or adjustments in the grinding operation as well as the provision of improved driving mechanism for rotating and reciprocating the respective parts while in operation.

A still further object is the provision of improved means for controlling and adjusting the various parts to meet the varying exigencies of actual service.

With the above mentioned, and other ends in view, the invention consists in the novel construction, arrangement and combination of parts, hereinafter described and illustrated in one of its embodiments in the accompanying drawings, and particularly pointed out in the appended claims.

Referring to the drawings, forming a part of this specification, Figure 1, is a central vertical sectional view of a machine constructed in accordance with this invention.

Fig. 2, a horizontal cross sectional view taken on line 2—2 of Fig. 1.

Fig. 3, a central longitudinal sectional view of the eccentrically mounted shaft carrying bearing sleeve and its adjustable bearings, detached.

Fig. 4, a cross sectional view taken on line 4—4 of Fig. 3.

Fig. 5, a cross sectional view taken on line 5—5 of Fig. 3.

Fig. 6, a cross sectional view taken on line 6—6 of Fig. 3.

Fig. 7, a cross sectional view taken on line 7—7 of Fig. 3.

Fig. 8, a top plan view of the same, certain parts of the gearing being broken away for the purpose of clearer illustration of the parts.

Fig. 9, an enlarged detail view of the flexible coupling or shaft at the upper end of the tool carrying driving shaft.

Similar numerals of reference designate like parts throughout all the figures of the drawings.

The improved machine comprises a stationary support or housing 1, the latter being provided with an attaching base 1^a provided with bolt receiving openings 1^b, for convenient attachment to the engine cylinder to be ground.

The support or housing 1, is provided, in the present instance, with a laterally extending gear housing 1^c, forming an oil reservoir to receive and contain the gearing hereinafter described. The gear housing 1^c, is provided, in the present instance, with a supporting bracket 1^d, for the convenient attachment and support of a suitable motor 2, for driving the driving or actuating mechanism.

As a means of vertically moving or reciprocating the abrading tool or grinding wheel 3, and the supporting and driving mechanism to which it is attached whereby such tool or grinding wheel is adapted to be lowered into and withdrawn from the subjacent cylinder and is given the requisite longitudinal movement therein during the grinding operation, a vertically movable support or carriage 4, is provided, said support or carriage 4, in the present instance, being of cylindrical form and provided at one side with a rack 4^a, engaging with a suitable pinion or gear 5, communicating with the driving mechanism hereinafter described, whereby such support or carriage 4, is actuated simultaneously with the rotation and planetary motion imparted to the abrading tool or wheel as hereinafter described. The support or carriage 4, is provided at its

ends with annular recesses or ball receiving race-ways 4^b, and centrally located bearing openings 4^c, adapted to receive and contain a rotatably mounted geared bearing support 5 or sleeve 6, said support or sleeve 6, being provided at its top with a gear wheel 6^a, said support or sleeve being preferably made in two parts so that the same may be longitudinally adjusted to take up wear and adjust 10 the annular ball bearings 7, the lower part 6^b, being secured, in the present instance, to the part 6, by means of a key member 6^c, as shown most clearly in Fig. 1, of the drawings. The two-part geared bearing support 15 or sleeve is also provided with centrally located openings 8, provided with annular cone-shaped shoulders 8^a, said openings 8, being adapted to receive and contain a shaft carrying bearing sleeve 9, the latter being 20 provided, in the present instance, with an integral bearing collar 9^a, at the lower end and at its upper end with an adjustable bearing collar 9^b, the latter being secured as against circumferential movement relative 25 to the bearing sleeve 9, by means of a key member 10.

As a means of connecting and drawing the bearing collars 9^a and 9^b toward each other and securely retaining the same in the seat 30 portions 8^a, of the openings 8, when adjusted, a connecting rod 11, is provided, (see Fig. 3.) said rod being provided with tapered shoulder portions 11^a, extending through and adapted to expand split portions 35 9^c, of the bearing collars when the nuts 11^b, are drawn up.

The bearing collars 9^a, and 9^b, are adapted to be adjusted circumferentially when the nuts 11^b, are loosened through the medium 40 of a wrench adapted to be inserted in the wrench receiving openings 9^d, of the adjusting collar 9^b, and the collars are provided with eccentric openings to receive and contain the lower end of the tool carrying 45 driving shaft 12, and the upper end of the shaft bearing sleeve 9, the latter being secured in the adjustable collar 9^b, by means of the retaining nut 13, threaded on the upper end of the shaft carrying sleeve 9.

50 By reason of the eccentric location of the tool carrying driving shaft 12, in the collars 9^a and 9^b, it is apparent that the shaft 12, may be readily adjusted so as to hold the grinding wheel or element 3, in contact with the inner surface of the cylinder and to a fixed distance from the center thereof and as the bearing support or sleeve 6, is revolved through the medium of the gear wheel 6^a, and the actuating mechanism hereinafter described, such grinding tool or element 3, will travel bodily in a circular path so as to effectively grind the entire surface 55 of the object being operated upon.

The upper end of the shaft 12, is provided with a flexible shaft or coupling 14,

and as a means of driving the shaft 12, and permitting the latter to be moved up and down with the reciprocation of the support or carriage 4, a gear wheel 15, is horizontally mounted between suitable bearings 1^a, 70 in a bracket 1^b, extending upwardly from the stationary support or housing 1. The gear wheel 15, is provided with a suitable key member or projection operating in a key-way 12^a, of the shaft 12. 75

As a means of transmitting motion to the parts 4, 6 and 12, a vertical driving shaft 16, is mounted at one end in the gear housing 1^c, and is supported at its upper end in suitable bearings 1^b, in laterally extending 80 bracket arms 1^b. A gear wheel 17, located between the arms 1^b, is adapted to transmit motion to the gear wheel 15, and a vertically movable gear wheel 18, on the shaft 16, is adapted to transmit motion to the gear 85 wheel 6^a, and is a means of holding the gear wheel 18, in alignment with the gear wheel 6^a, and causing the gear wheel 18, to be moved up and down with the reciprocation of the carriage 4, and the geared bearing 90 sleeve 6, said gear wheel 6^a, is provided with removable guide flanges 6^d, adapted to receive and contain the outer edges of the gear wheel 18. The gear wheel 18, is provided with a key adapted to operate in a key-way 95 16^a, of the shaft 16.

The shaft 16, may be provided with a bevel-gear 19, meshing with a second bevel-gear 20, on the motor shaft, and as a means of transmitting motion to the gear wheel 6^a, 100 whereby the latter is adapted to reciprocate the carriage 4, the lower end of the shaft 16, is provided with a worm 21, meshing with a worm-gear 22, on a horizontally extending shaft 23, mounted in suitable bearings in the gear housing 1^c, and the shaft 23, is provided with a worm 23^a, meshing with a gear 24, carried on a shaft 25, mounted in bearings 26, and the shaft 25, is provided with a pinion 27, meshing with the gear 5, operating in the rack 4^a. 105

It will also be apparent that by reversing the motor the direction of rotation or reciprocation of the parts will be correspondingly reversed and it will be seen that 115 an improved machine of great strength and rigidity in which the bearings may be readily adjusted, is produced.

From the foregoing description, taken in connection with the accompanying drawings, the operation and advantages of my invention will be readily understood.

Having thus described one of the embodiments of my invention, what I claim and desire to secure by Letters Patent is, 120 125

1. In a machine for grinding cylinders, the combination with a shaft carrying bearing sleeve provided with eccentrically arranged bearing collars having split portions at one side; of a connecting rod having ta- 130

pered shoulder portions extending through and connected to said split portions whereby the latter may be expanded and secured in adjusted position.

5. 2. A machine for grinding cylinders, comprising a stationary support, a carriage vertically movable therein, a relatively mounted geared bearing support in said carriage, a tool carrying driving shaft, a shaft carrying bearing sleeve eccentrically and adjustably mounted in said geared bearing support and provided with cone-shaped split bearing collars, means for expanding the latter, and means for simultaneously moving said carriage and driving said driving shaft and said geared bearing support whereby said driving shaft is given a combined vertical and planetary motion.

3. In a machine for grinding cylinders, a stationary support, a vertically movable carriage therein, a two-part geared bearing sleeve removably mounted in said carriage, a tool carrying driving shaft provided with eccentric bearing collars removably and adjustably mounted in said geared bearing sleeve, and driving mechanism operatively connected to said carriage driving shaft, and geared support whereby said grinding wheel carrying shaft is given a gyratory motion.

4. In a machine for grinding cylinders, a shaft carrying bearing sleeve provided with eccentrically arranged bearing collars having cone-shaped split portions, one of said collars being removable and adjustable on said shaft carrying bearing sleeve, and a connecting rod provided at its ends with tapered shoulder portions extending through and connected to said cone-shaped split portions, and adjusting nuts on the ends of said rod whereby to expand said split portions when said nuts are drawn toward said tapered shoulder portions.

5. A machine for grinding cylinders, comprising an attaching base member, a cylindrical carriage vertically movable therein and provided at its opposite ends with ball race-ways, a two-part geared bearing sleeve mounted in said carriage and provided with coöperating ball race-ways and centrally located openings, a shaft carrying bearing sleeve provided with eccentrically arranged collars in said bearing openings, and means for connecting and adjusting said collars whereby to adjust the eccentric relation of said shaft carrying bearing sleeve.

6. In a machine for grinding cylinders, the combination with a two-part geared bearing sleeve having bearing openings ter-

minating in cone-shaped shoulders and also provided with annular bearing portions; of a two-part shaft carrying bearing sleeve having collars mounted in said bearing openings and provided with cone-shaped shoulders coöperating with said first mentioned cone-shaped shoulders, and means for connecting and adjusting said collars whereby to adjust said two-part geared bearing sleeve and said annular bearing portions relative to each other.

7. In a machine for grinding cylinders, the combination with a vertically movable carriage provided at its ends with ball race-ways and centrally located openings, and a two-part geared bearing sleeve provided at its ends with coöperating ball race-ways and bearing openings terminating in annular cone-shaped shoulders; of a shaft carrying bearing sleeve provided with eccentrically arranged bearing collars mounted in said openings and seated on said cone-shaped shoulders, and means for connecting and adjusting said bearing collars whereby to adjust said ball race-ways through said two-part geared bearing sleeve.

8. A machine for grinding cylinders, comprising a stationary geared bearing sleeve rotatively mounted in said carriage, a shaft carrying bearing sleeve provided with eccentrically mounted bearing collars adjustably mounted in said geared bearing sleeve, means for adjusting and securing said collars in said bearing sleeve, a tool carrying driving shaft mounted in said shaft carrying bearing sleeve and provided at its upper end with a flexible coupling, a shaft connected to said coupling and provided with a longitudinal key-way, a gear wheel adapted to slidably receive said shaft and provided with a key member extending into said key-way, a vertical driving shaft provided with a gear wheel meshing with said gear wheel, a second gear wheel slidably mounted on said driving shaft, and a gear wheel mounted on said rotatively mounted bearing sleeve and provided with guide flanges receiving and taking over the edges of said last mentioned gear wheel whereby the latter is held in alinement and shifted simultaneously with the vertical movements of said carriage.

In testimony whereof I have affixed my signature in presence of two witnesses.

JOHN JAY LESCHER.
